UNITED STATES PATENT OFFICE

HARRY P. SPARKES AND FERNALD S. STICKNEY, OF WEST ORANGE, NEW JERSEY, ASSIGNORS TO WESTINGHOUSE ELECTRIC AND MANUFACTURING COMPANY, A CORPORATION OF PENNSYLVANIA

DESIGN FOR A CASING FOR TEMPERATURE INDICATORS

Application filed June 9, 1932. Serial No. 44,036. Term of patent 7 years.

To all whom it may concern:

Be it known that we, HARRY P. SPARKES and FERNALD S. STICKNEY, citizens of the United States, residing at West Orange, in the county of Essex and State of New Jersey, have invented a new, original, and ornamental Design for Casings for Temperature Indicators, of which the following is a specification, reference being had to the accompanying drawing, constituting a part hereof.

Figure 1 is a view in front elevation of a casing for a temperature indicator showing our new design;

Fig. 2 is a view in side elevation of the casing shown in Fig. 1; and,

Fig. 3 is a view taken along the lines III—III of Fig. 1.

We claim:

The ornamental design for a casing for temperature indicators substantially as shown.

In testimony whereof, we have hereunto subscribed our names this 19th day of May, 1932.

HARRY P. SPARKES.
FERNALD S. STICKNEY.
